UNITED STATES PATENT OFFICE.

JOHN I. BELLAMY, OF BROOKFIELD, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed October 30, 1924, Serial No. 746,730. Renewed October 15, 1928.

The present invention relates to telephone systems in general, but is concerned more particularly with automatic telephone systems; and the broad general object is the production of a new and improved telephone system in which the apparatus employed is considerably simplified and its operation improved.

Specifically, one object of the invention is the production of a new and improved automatic substation circuit of the so-called "booster" type which uses a standard calling device with a pair of impulse contacts and three shunt springs, and having a simple switchhook spring combination.

Another object is the production of a new and improved circuit arrangement whereby the line relay of a rotary line switch individual to a calling subscriber's line is employed on calls originated on the associated line to connect up the wipers of the line switch and to maintain them connected throughout the connection so as to obviate the necessity of the usual mechanical interlocking device which is otherwise employed to prevent the combined cut-off and switching relay from pulling all the way up and connecting the associated line to the switch wipers on incoming calls.

Another object is the production of novel circuit arrangements whereby the calling subscriber's meter is controlled over the release trunk conductor by an electro-polarized relay associated with a first selector, as will hereinafter appear.

Another object is concerned with the production of a new and improved circuit arrangement for controlling the slow-acting change-over relay of a switch in such a manner that the relay falls back in the same time at the end of a series of impulses in all cases, irrespective of the length of the individual impulse constituting the series.

A still further object has to do with so-called "directors" which are employed primarily in order to enable a more economical inter-office trunking layout to be used in a multi-office telephone system to which the universal directory is applied, and the feature of improvement consists in the provision of an intermediate distributing frame (employed in order to permit the ready translation of the office digits of a telephone number into the necessary code digits re-

quired to trunk the call to the desired office) which is common to a plurality of directors instead of being individual to one director.

Another object is the production of a new and improved counting relay circuit for operating nonmarginal counting relays, in which a minimum of relays are employed.

There are a number of other objects and features of the invention which, however, are more or less incidental to the carrying out of the objects set forth above. These latter objects and features, together with the foregoing, will become apparent upon a further perusal of the specification.

Referring now to the accompanying drawings comprising Figs. 1-5, inclusive, they show by means of the usual circuit diagrams, a sufficient amount of apparatus in a telephone system embodying the principles of the invention to enable the invention to be understood. Fig. 1 shows the apparatus necessary to extend a connection from a calling line to a first selector and also a director selector DS for associating an idle director with the connection until it is completed, and Figs. 2-5, inclusive, show one of the directors accessible to the director selector shown in Fig. 1.

Specifically, Fig. 1 shows the substation A and the associated line which terminates at the exchange in the line switch LS and also in the bank of connector switches (not shown). This drawing shows also the selector S accessible to the line switch LS and likewise the trunk circuit TC which is inserted in the trunk between the banks of the line switch LS and the selector S and which has associated with it the director selector DS, which, as above pointed out, has access to a number of directors, one of which is the one shown in Figs. 2-5, inclusive.

Regarding the apparatus shown, the substation A, Fig. 1, is—from the standpoint of the major pieces of apparatus—of the usual automatic type having the usual talking, signalling, and switch controlling instrumentalities, but from a circuit standpoint and from the standpoint of the circuit closing and opening spring contacts required the substation has been greatly simplified and improved, as will hereinafter appear.

The line switch LS individual to the line of substation A is mechanically of the well

known rotary type in which the wipers have no normal position, but are advanced in a forward direction only, being advanced upon the backward stroke of the associated 5 stepping magnet rather than upon the forward stroke; but from a circuit standpoint, the line switch is novel in that the line relay 16 constitutes means whereby the wipers are connected up on outgoing calls only, therefore 10 by permitting the usual mechanical interlocking device between the armatures of the two relays of the line switch to be omitted.

The selector S, mechanically, is of the well known vertical and rotary type of 15 switch having bank contacts which are arranged in horizontal rows or levels, but from a circuit standpoint contains a certain novel feature which will be pointed out hereinafter.

20 The director selector DS is similar mechanically to the line switch LS, and is connected up to the trunk circuit TC in such a manner that it operates to select an idle director when the associated trunk is seized, 25 the trunk circuit TC being novel only in that it contains arrangements for permitting the calling subscriber to hear the impulses as they are transmitted by a director to position the automatic switches as will 30 be pointed out hereinafter.

The sequence switch S, Fig. 2, of the 35 director, is mechanically of a simple type of switch, having the wipers 108 and 109 which are advanced step by step by the stepping magnet 105 and which are subsequently restored to normal under the control of release magnet 106 which is provided with the off normal contacts 107 to open its circuit when the normal position is reached, 40 and is provided with the relays 101 and 102 through the medium of which it is advanced one step at the end of each series of impulses transmitted to the director from the trunk circuit TC.

45 The office register OR, Fig. 4, is mechanically of the well known vertical and rotary type of switch, having its bank contacts arranged in horizontal rows or levels, and it responds to the first two digits dialled by 50 the calling subscriber and positions its wipers upon the set of bank contacts corresponding to the called office, preparatory to the transmission of such digits as are necessary to trunk the call from the originating office to the called office.

55 Each of the digit registers DR-1-DR-4, inclusive, Fig. 5, is, from a mechanical standpoint, similar to the sequence switch S, Fig. 2, and each is operated to register 60 one of the subscriber digits of a number following the registration of the office digits of the number by the office register OR, Fig. 4.

The sequence switch S', Fig. 2, is, from a 65 mechanical standpoint, a rotary switch of

the well known type in which the wipers are advanced in a forward direction only and are advanced upon the backward stroke of the stepping magnet rather than upon the forward stroke, and is used to control, 70 successively, the transmission of the various digits of the number in their proper sequence.

The counting relays 403 and 411-420, inclusive, operate in conjunction with certain 75 of the relays shown in Fig. 3 to control the transmission of the impulses constituting the digits and to terminate such transmission at the proper time, as will be herein-after explained.

80 Referring now particularly to the intermediate distributing frame IDF, Fig. 4, and the associated apparatus, this intermediate distributing frame is provided for the purpose of enabling the office codes to 85 be changed readily at any time. In accordance with this, the intermediate distributing frame shown in the drawings has been made common to a plurality of directors instead of being individual to one 90 director, as is usually the case, for the sake of economy, and also so that the changing of the jumpers at one point affects all directors to which the intermediate distributing frame is common.

95 Another and very important advantage gained by making the intermediate distributing frame common to a plurality of directors is that the office registers may be mounted side by side with their banks multiplied together as in the case of ordinary automatic switches.

In order to enable the distributing frame to be made common to a plurality of directors, a common counting switch CS has been 100 provided. This counting switch is operated under the control of an interrupter 304 which is driven at the same speed and in synchronism with the various associated interrupters, one for each director to which 105 the distributing frame is common. The counting switch CS has, in addition to the ten impulse conductors 311-320, inclusive, a common pick-up conductor 303 which extends to each of the associated directors and 110 which controls the time of the starting of the transmission of impulses by the directors.

115 The apparatus having been described more or less in general, a detailed description of its operation will now be given. For this purpose, it will be assumed that the subscriber at substation A, desiring to make a call, removes his receiver.

120 When the receiver is removed at substation A, the switchhook 7 rises and closes a direct current bridge across the line conductors 11 and 12 which includes the impulse springs 5 of the calling device, the transmitter 6, and the upper winding of the in- 125

duction coil 4. When this occurs, line relay 16 of the line switch LS energizes and connects up the wipers 28-31, inclusive, at the armatures 23, 24, 26, and 27, and at armature 25 closes a circuit for switching relay 15 and stepping magnet 14 in series, at the same time placing ground on the private normal conductor 13 so as to make the calling line busy in the banks of the connector 10 switches having access to it.

It will be noted that test wiper 29 is now connected to the junction of switching relay 15 and stepping magnet 14 through the working contact and armature 24, and armature 20 and its resting contact; and that test wiper 30 is connected, through the working contact and armature 26, and armature 21 and its resting contact, also to the junction of switching relay 15 and stepping magnet 14. Accordingly, the junction of switching relay 15 and stepping magnet 14 is grounded in case there is a ground potential applied to the conductor upon which test wiper 29 is standing or to the conductor 25 upon which test wiper 30 is standing (the utility of the provision of two test wipers will become apparent upon a further perusal of the specification).

From this point on, the operation depends upon whether the trunk terminating in the bank contacts upon which the wipers of the line switch are standing is busy or idle. If it is idle, there is no ground potential upon the bank contacts engaged by test wipers 29 and 30 and switching relay 15 energizes, seizing the trunk. On the other hand, in case the trunk is busy, switching relay 15 is short circuited by the ground potential encountered upon the busy test contact by test wiper 29 or by test wiper 30 and does not energize, and the wipers are advanced step by step by the buzzer-like action of stepping magnet 14, which operates through either of the test wipers 29 and 30. This operation continues until an idle trunk is reached, which trunk, it may be assumed, is the one comprising conductors 36-38, inclusive, and extending to the trunk circuit TC. When this idle trunk is reached, no ground is encountered by either of the test wipers 29 and 30, and switching relay 15, being no longer short circuited, energizes in series with stepping magnet 14. Stepping magnet 14 does not energize at this time on account of the high resistance of switching relay 15. Upon energizing, relay 15 disconnects test wiper 30 from the junction of its own winding and that of stepping magnet 14 at armature 21, at the same time connecting test wiper 30 to ground so as to make the seized trunk busy by way of the local test conductor 34 which, together with conductors 32, 33, and 35, is multiplied to the bank contacts of all the line switches having 65 access to this trunk. As a further result of

the energization of switching relay 15, the line conductors 11 and 12 are disconnected from line relay 16 and ground, respectively, at armatures 18 and 22 and are connected to the line conductors 36 and 38 of the seized 70 trunk through armatures 23 and 27 and wipers 28 and 31. As a still further result of the energization of switching relay 15, it disconnects test wiper 29 from the junction of its own winding and that of stepping 75 magnet 14 and connects it instead to line relay 16, and at armature 19 connects the test wiper 29 to the marginally adjusted meter M. Line relay 16 is now disconnected and no current is flowing through it, but so it remains energized during this interval owing to the fact that it is slow acting.

In the trunk circuit TC, line relay 41 now energizes over the calling line and over conductors 36 and 38 and closes at armature 44 a circuit for release relay 42 which thereupon energizes and places ground upon conductor 40 of the selector S at armature 46, thereby closing a circuit through the resistance 84, holding conductor 37, test wiper 29 of the line switch LS, working contact and armature 24, and armature 20 and its working contact for line relay 16 of the line switch LS before it has had time to deenergize. The meter M, whose magnet 17 is now connected 95 in multiple with line relay 16 through the working contact and armature 19 of switching relay 15, is not operated at this time owing to its marginal adjustment and owing to the relatively high resistance 84 in 100 the selector S.

As a further result of the energization of release relay 42 of the trunk circuit TC, it closes at armature 46 a circuit for switching relay 52 and stepping magnet 53 of the 105 director selector DS in series, and, at armature 48 connects test wiper 60 to the junction of relay 52 and magnet 53. Accordingly, the director selector DS selects an idle director in much the same manner as 110 above described for the line switch LS, which director, it will be assumed, is the one reached by way of conductors 62-65, inclusive. When the selection of this director occurs, switching relay 52 is no longer 115 short circuited and energizes in series with stepping magnet 53, which magnet does not energize at this time on account of the high resistance of switching relay 52; opens the test circuit and grounds conductor 64 at 120 armature 56 and through wiper 60; connects up the operating circuit at armature 57 and through wiper 61 to conductor 65 of the director; and at armatures 54 and 55 connects the line conductors of the selector 125 S to wipers 58 and 59 which are now standing upon the bank contacts in which the outgoing impulse conductors 62 and 63 of the director terminate. These conductors are normally closed together through arm- 130

tures 230 and 232 of relays 204 and 205, Fig. 3. Accordingly, line relay 72 of the selector S now energizes and closes at armature 87 a circuit for release relay 73. When this occurs, relay 73 energizes and prepares the selector for operation by operating armature 88.

In the seized director, holding relay 203 energizes responsive to the ground potential being placed upon the release trunk conductor 64 by the director selector DS as above pointed out, and at armatures 227 and 229 opens the two release circuits of the director, while, at armature 228, it places ground upon the locking conductor 242 through armature 238 and its resting contact, for a purpose which will be made plain later.

The above operations have all taken place responsive to the removal of the receiver at the calling substation A, Fig. 1, and the apparatus is now in position for the first digit of the number to be dialled.

When the calling subscriber rotates the well known finger hold dial of his calling device forward in accordance with the first digit in the desired number, the so-called "shunt" springs 9 come together and short circuit the transmitter 6 and the receiver 8, so as to eliminate the resistance of the transmitter 6 from the line circuit during dialling and so as to prevent the production of disagreeable clicks in the receiver 8. As the finger hold of the calling device rotates back to normal, the interrupter contacts 5 are separated a number of times corresponding to the position to which it was moved upon the forward rotation. Each time the circuit is interrupted at the contacts 5, line relay 41 of the trunk circuit TC deenergizes, and at armature 45 places ground on conductor 65 of the director through armature 57 and its working contact and wiper 61. Each time ground is placed upon conductor 65, an impulse of current is delivered through series relay 101, wiper 109 of the sequence switch S and conductor 111 to the vertical magnet 325 of the office register OR. Accordingly, the vertical magnet 325 is operated a number of times corresponding to the first digit dialled, and by the operation of vertical magnet 325 the wipers 321-324, inclusive, are raised step by step until they stand opposite the desired level of bank contacts. Relay 101 is energized in series with vertical magnet 325 and, being slow acting, maintains its armature 103 attracted throughout the vertical movement. At armature 103, relay 101 closes a circuit for the associated slow acting relay 102, which energizes and prepares a circuit for the stepping magnet 105 of the sequence switch S at armature 104.

At the end of the vertical movement, se-

ries relay 101 deenergizes and completes at armature 103 a circuit for stepping magnet 105 which is opened a moment later upon the deenergization of the slow acting relay 102. Responsive to the momentary closure 70 of its circuit, stepping magnet 105 energizes and advances the wipers 108 and 109 one step, thereby shifting the operating circuit from the vertical magnet conductor 111 to the rotary magnet conductor 112 leading to 75 the office register OR.

When the calling subscriber manipulates his calling device in accordance with the second digit in the desired number, conductor 65 is grounded a number of times 80 corresponding to the digit dialled and, each time it is grounded a circuit is closed through series relay 101, wiper 109, and overconductor 112 for rotary magnet 326 of the office register OR. Accordingly, the 85 wipers 321-324, inclusive, are rotated step by step by the action of rotary magnet 326 until they come into engagement with the desired set of bank contacts, which set, it will be assumed, is the one comprising contacts 331-334, inclusive.

The sequence switch S is now advanced one step in the hereinbefore described manner, and wiper 109 shifts the operating circuit over to conductor 121 associated with 95 the first digit register DR-1, Fig. 5. At the same time, wiper 108 connects the common pick-up conductor 303 with the individual pick-up conductor 119 upon coming into engagement with its third bank contact. The description of the effect of this operation, however, will be deferred until the description of the registration of the desired number is completed.

When the calling subscriber manipulates 105 his calling device in accordance with the first subscriber digit in the desired number, the resulting series of impulses is transmitted over the operating conductor 65 through series relay 101, wiper 109 of the sequence 110 switch S, and over conductor 121 to the stepping magnet of the digit register DR-1 which responds to these impulses and sets the associated wiper upon the corresponding bank contact.

In the same way the digit register DR-2 responds to the second subscriber digit; the digit register DR-3 responds to the third subscriber digit; and the digit register DR-4 responds to the fourth subscriber 120 digit, at the end of which the wipers 108 and 109 of the sequence switch advance one step in the usual manner, as it does at the end of each digit, and the wipers come to rest and do not again move until the director is freed.

The utility of connecting the common pick-up conductor 303 to the individual pick-up conductor 119 at wiper 108 of the sequence switch S is to start the sending 130

apparatus of the director to transmit the first code digit necessary to trunk the call to the desired office. This may well be done at this time, since, as above pointed 5 out, the two pick-up conductors are joined just subsequent to the registration of the second and last office digit.

It will be noted that the interrupters 304-308, inclusive are all operated in synchronism with each other and that they are all alike with the exception of the interrupter 304 which controls the counting switch CS. The conducting portion of the interrupter 304 comes under the associated brush a little 10 sooner than the conducting portions of the other interrupters come under their associated brushes. The insulated segments of all the interrupters, however, come under their brushes at the same time. The reason 15 for this difference will be brought out later. It may be seen that the stepping magnet 309 of the counting switch CS is alternately energized and deenergized under the control of the interrupter 304, being deenergized while 20 the insulating portion of the interrupter is under the brush, and being energized while the conducting portion of the interrupter is under the associated brush. It may be seen further that the wiper 310 is advanced step 25 by step under the control of magnet 309 and that the wiper 310 is advanced upon the back stroke of stepping magnet 309 and consequently is advanced upon the opening of the interrupter 304 rather than upon its 30 closing. It may be seen further that the wiper 310 is grounded and extends ground to the bank contact upon which it is standing only while the magnet 309 is deenergized between steps, and that ground is removed 35 from the wiper 310 as soon as magnet 309 energizes for the next step which it does just a little ahead of the closure of the interrupters 305 to 308, inclusive, for a purpose to be explained more fully later.

To continue with the detailed description 40 of the operation in setting up the connection now under discussion, as soon, after the common conductor 303 is connected with the individual pick-up conductor 119 by wiper 45 108 of the sequence switch S, as the wiper 310 arrives in its pick-up position, i. e., in the position in which it is standing upon the contact associated with conductor 303, the common pick-up conductor 303 is grounded 50 through the contact 329, thereby closing a circuit over conductor 303, through wiper 108 of the sequence switch S, individual pick-up conductor 119, armature 222 and its resting contact, resting contact and armature 224, and the normally closed contacts 55 controlled by armature 235 for the pick-up relay 205. When this circuit is closed, pick-up relay 205 energizes and locks itself to conductor 242 at armature 235 at the same 60 time opening its initial circuit, conductor 65

242 being grounded at this time through the resting contact and armature 238 and armature 228 and its working contact. As a further result of the energization of pick-up relay 205, it connects ground to the upper 70 terminal of the impulse relay 204 at armature 234 through a circuit which includes armature 239 and its resting contact, and the resting contacts and armature 237. It will be appreciated that this occurs at a 75 time when all the interrupters 304-308, inclusive, are opened. Accordingly, the sending relay 204 does not immediately energize.

As a still further result of the energization of pick-up relay 205, Fig. 3, it removes 80 the shunt from around armature 230 and its resting contact of the sending relay 204 at armature 232, thereby placing the bridge across the outgoing control conductors 62 and 63 under the control of the sending re- 85 lay 204, and at armature 233 places ground upon conductor 116 through armature 236 and its resting contact, thereby closing a circuit for stepping magnet 113 of the sending control sequence switch S'. According- 90 to advancing the wipers 114 and 115.

As the interrupters 304-308, inclusive, advance still further, the interrupter 304 closes first and closes a circuit for stepping 95 magnet 309 of the counting switch CS which accordingly energizes and removes ground from conductor 303 at armature 329, thereby preventing any further pick-up relays in the other directors from energizing at this time 100 and until the wiper 310 comes around with the pick-up position again. A little later, the interrupters 305-308, inclusive, close simultaneously and, upon the closure of interrupter 305, a circuit is closed over con- 105 ductor 110 for relay 204, Fig. 3, whose upper terminal was previously grounded at armature 234 by pick-up relay 205. When this occurs, impulse relay 204 energizes and opens the bridge across conductors 62 and 63 at 110 armature 230. Following this interruption of the outgoing control circuit by relay 204, the interrupters all open at the same time, whereupon the impulse relay 204 deenergizes 115 and again closes the outgoing control circuit and stepping magnet 309 of the counting switch CS deenergizes and advances wiper 310 into engagement with the first stop conductor 311, at the same time placing ground on the said stop conductor 311 at contacts 120 329. It may be well to point out that the contacts 329 do not close until after the wiper 310 has been advanced out of engagement 125 with the bank contact in which the common pick-up conductor 303 terminates and the pick-up conductor 303 is not again grounded at this time. Since the first code digit to be transmitted is not the digit 1 but is, instead, the digit 0, the placing of ground upon the first impulse stop conductor 311 does not 130

produce any results as regards the director shown at this time, and the operation of the counting switch CS continues and the outgoing control circuit continues to be interrupted by the impulse relay 204, Fig. 3, in the manner described above until wiper 310 arrives upon the bank contact in which the tenth impulse stop conductor 320 terminates, at which time ten interruptions have been 10 produced in the outgoing control circuit, whereupon stop relay 207, Fig. 3, energizes over the following circuit: from ground by way of the contacts 329 of the counting switch CS, Fig. 4, wiper 310, the tenth impulse stop conductor 320, jumper 335, the first bank contact 331 in the set of bank contacts belonging to the called office, wiper 321, the first code digit stop conductor 131, first contact in the bank of wiper 115 of 20 the sequence switch S' and said wiper, conductor 120, armature 223 and its resting contact, the marginally adjusted skip relay 202, working contact and armature 243, and stop relay 207 to battery. When this circuit 25 is closed, the marginal skip relay 202 does not energize, but stop relay 207, which may be considered somewhat in the capacity of an auxiliary stop relay, energizes and disconnects ground from the upper terminal of 30 relay 204 and closes a circuit for stop relay 206 at armature 239. Stop relay 206 now energizes; opens a further point in the circuit of relay 204 at armature 237; opens the circuit of stepping magnet 113 of the 35 sequence switch S' and closes a locking circuit for itself at armature 236; and at armature 238 removes ground from the conductor 242, thereby opening the locking circuit of pick-up relay 205. Pick-up relay 205, however, 40 is slow acting and does not deenergize for the time being. As a result of the opening of the circuit of stepping magnet 113 of the sequence switch S' by stop relay 206, stepping magnet 113 deenergizes and advances 45 the wipers 114 and 115 one step and wiper 115 comes into engagement with the bank contact in which the second code digit stop conductor 132 terminates, preparatory to the subsequent termination of the second code digit.

In the selector S, line relay 72 deenergizes responsive to each of the above interruptions in the outgoing control circuit of the director at armature 230 of relay 204, Fig. 3, and, 55 upon each deenergization, closes at armature 87 a circuit for vertical magnet 81 through armature 88 and its working contact. By the operation of vertical magnet 81, the wipers 96-98, inclusive, of the selector are raised step by step and come to rest opposite the desired level of bank contacts. Relay 74 is energized in multiple with vertical magnet 81 through the contacts 82 of vertical magnet 81 upon each impulse of current 60 being transmitted to vertical magnet 81.

The contacts 82 are adjusted to open just at the completion of the stroke of vertical magnet 81, thereby insuring that all impulses of current transmitted to the slow acting relay 74 are of the same length and this length 70 cannot be longer than the time required for vertical magnet 81 to energize after its circuit is closed, and if the impulse delivered by armature 87 of line relay 72 on its back stroke is not of this length, the vertical magnet 75 fails which means that, upon any impulse being transmitted to vertical magnet 81 which is of sufficient length to operate the said vertical magnet 81, relay 74 receives an impulse of current of an unvarying 80 length except, of course, for the variation in the length of time required for vertical magnet 81 to operate from time to time. Relay 74, being slow acting, maintains its armature 89 attracted throughout the vertical movement, and, upon the closure of off normal contacts 81, which occurs at the end of the first vertical step, a circuit is closed through the interrupter contacts 80 for the stepping relay 75. Upon energizing, relay 90 75 closes a locking circuit for itself at armature 90 and at armature 91 prepares a circuit for rotary magnet 79.

At the end of the vertical movement, the slow acting relay 74 deenergizes and closes 95 at armature 89 a circuit through armature 91 and its working contact for rotary magnet 79 which energizes and advances the wipers 96-98, inclusive, into engagement with the first set of bank contacts in the selected 100 level, and, near the end of its stroke, opens the circuit of stepping relay 75 at the interrupter contacts 80. When this occurs, stepping relay 75 deenergizes and opens the circuit of rotary magnet 79 at armature 91, 105 whereupon rotary magnet 79 deenergizes also and again closes its interrupter contacts 80.

From this point on, the operation depends upon whether the trunk terminating in the 110 first set of bank contacts is busy or idle. If it is idle, switching relay 76 energizes, seizing the trunk. On the other hand, if the trunk is busy, switching relay 76 is short circuited by the ground potential encountered upon the busy test contact by test wiper 97 and does not energize. Also, stepping relay 75 energizes again through test wiper 97 and again closes its locking circuit at armature 90, and at armature 91 again closes 115 the circuit of rotary magnet 79. Rotary magnet 79 energizes again and advances the wipers into engagement with the next set of bank contacts. This alternate operation of stepping relay 75 and rotary magnet 79 continues as described until an idle trunk is 120 reached, which trunk, it will be assumed, is the one shown in the drawings and having the release trunk conductor 99. When this occurs, switching relay 76, being no longer 125 130

short circuited, energizes in series with stepping relay 75. Stepping relay 75, however, does not energize at this time on account of the relatively high resistance of switching relay 76. Upon energizing, relay 76 disconnects ground from armature 87 of line relay 72 at armature 94, thereby opening the circuit of release relay 73; opens the test circuit and prepares the holding circuit at 10 armature 93; and at armatures 92 and 95 disconnects the line conductors of the switch from line relay 72 and connects them to the wipers 96 and 98 instead, whereupon the line relay of the switch to which the seized 15 trunk extends energizes and closes a circuit for the associated release relay which pulls up and places ground upon release trunk conductor 99, thereby closing the usual holding circuit which becomes effective upon the 20 subsequent deenergization of the slow acting relay 42 of the trunk circuit TC to hold up the established connection.

In the director, the slow acting pick-up relay 205 deenergizes after the interval for 25 which it is adjusted, responsive to the opening of its locking circuit at armature 238 of stop relay 206, and opens the locking circuit of stop relay 206 at armature 233. Stop relay 206 also is slow acting and does not de- 30 energize immediately. After an interval, however, stop relay 206 also deenergizes and again connects up pick-up relay 205 at armature 244, and at armature 237 prepares a circuit for stepping relay 204.

35 It may be well to point out at this time that the dead contacts passed over by the wiper 310 after it passes beyond the contact in which the tenth impulse stop conductor 320 terminates, are provided for the 40 purpose of permitting the slow acting relays 205 and 206 to deenergize and again close the pick-up circuit after conductor 320 is passed and before pick-up conductor 303 is reached. Otherwise, if these contacts were 45 not provided and if the pick-up position was passed immediately after the tenth impulse contact was passed, an unnecessary length of time would be consumed following the termination of the digit 0 and 50 other long digits while waiting for the pick-up position to be reached the second time.

To continue with the description of the 55 operation, as soon as the common pick-up conductor 303 is grounded again, the previously traced circuit for pick-up relay 205, Fig. 3, is again closed, whereupon pick-up relay 205 energizes and closes a locking circuit for itself and the second code digit is transmitted in the same way as the first. This 60 second code digit is the digit 5. Accordingly, at the end of the fifth interruption in the outgoing control circuit at armature 230 of impulse relay 204, Fig. 3, the second code digit 5 is terminated upon the energization 65 of stop relay 207 over the following circuit

responsive to the grounding of the fifth impulse stop conductor 316 by the counting switch CS: from ground by way of contact 329, wiper 310, the fifth impulse stop conductor 315, jumper 336, the second bank 70 contact 332, the second wiper 322, the second code digit stop conductor 132, wiper 115 of the sequence switch S', conductor 120, armature 223 and its resting contact, marginal relay 202, working contact and armature 75 243, and stop relay 207 to battery. The sequence switch S' is automatically advanced in the hereinbefore described manner upon the termination of this digit and wiper 115 connects stop conductor 120 to the third code 80 digit stop conductor 133 preparatory to the termination of the third code digit 2.

Responsive to the transmission of the second code digit 5, the selector switch seized by the selector S in response to the transmission of the first code digit 0, raises its wipers to the fifth level and selects an idle 85 trunk in the usual manner.

In the director, pick-up relay 205 is operated again upon the next grounding of the common pick-up conductor 203 and the transmission of the third and last code digit 2 begins, and, upon the termination of the second interruption in the outgoing control circuit by the impulse relay 204, stop relay 207 energizes over the following circuit: from ground by way of contact 329 of the counting switch CS, wiper 310, the third impulse stop conductor 312, jumper 357, the third bank contact 333, the third wiper 323, the third code digit stop conductor 133, wiper 115 of the sequence switch S', conductor 120, and, as previously traced, to stop relay 207 and battery. Upon the energization of stop relay 207, this digit is terminated in 105 the usual manner and the wipers of the sequence switch S' are again advanced.

Responsive to the transmission of the third code digit 2, the selector taken into use responsive to the transmission of the second 110 code digit 5 raises its wipers to the second level and selects a trunk line leading to the called office.

In the director, the sequence switch S' is advanced automatically through the fourth 115 code digit position immediately following its advance into the fourth code position as above pointed out. The reason for the automatic advance to the fourth code digit position is that only three code digits are necessary in this case to trunk the call to the desired office, and it is necessary, therefore, to skip the fourth code digit position in order to transmit the first subscriber digit. The way in which this position is skipped will 120 now be pointed out. Upon referring to the intermediate distributing frame IDF, Fig. 4, it will be noted that the fourth bank contact 334 in the selected set instead of being cross-connected to one of the impulse stop con- 125 130

ductors, is cross-connected to the skip conductor 302, which conductor is connected with the booster battery 301, which battery has its negative pole grounded instead of the positive pole. Accordingly, upon the advance of wiper 115 into the fourth code digit position, a circuit is completed as follows: from ground by way of the booster battery 301, Fig. 3, skip conductor 302, jumper 338, 10 contact 334, wiper 324, conductor 134, wiper 115, conductor 120, armature 223 and its resting contact, the marginally adjusted skip relay 202, working contact and armature 243, and stop relay 207 to battery. Stop relay 207 15 which was previously energized in the third position of the sequence switch S' remains energized when the sequence switch advances into the fourth position and the marginally adjusted relay 202 now energizes on account 20 of the increased current occasioned by the introduction of the booster battery 301 into the circuit in series with the regular exchange battery. Upon energizing, relay 202 closes at armature 226 a circuit over conductor 118 and through the local interrupter contacts of stepping magnet 113 for the said stepping magnet 113 in multiple with relays 202 and 207. Accordingly, stepping magnet 113 energizes and interrupts its own circuit, 25 whereupon it deenergizes and advances the wipers 114 and 115 into engagement with the next set of bank contacts. The automatic operation of the sequence switch S' ceases now because wiper 115 engages an open contact and relays 202 and 207 fall back. Responsive to wiper 114 coming into engagement with the fifth associated bank contact, change-over relay 201 energizes over the following circuit: from ground by way of relay 201, conductor 117, fifth contact in the bank 30 of wiper 114 and said wiper, local interrupter contacts of the switch S', and stepping magnet 113 to battery. Stepping magnet 113 does not energize at this time, 35 however, on account of the high resistance of relay 201. Upon energizing, relay 201 disconnects wiper 115 from relays 202 and 207 and connects it to ground instead at armature 223; disconnects pick-up conductor 119 from pick-up relay 205 at armature 222; prepares a circuit for relays 208 and 209 at armature 224; at armature 221 prepares a circuit for impulse relay 204 which is independent of pick-up relay 205; and at armature 225 connects the first subscriber-digit stop conductor 141 to the corresponding contact in the bank of wiper 115. 40

In summation of the result of the operation of the change-over relay 201, it may be pointed out that the circuits are now shifted so that the director is ready to transmit impulses under the control of the local counting relays 411-420, Fig. 5, rather than under the control of the common counting switch 45 CS, Fig. 4. This change is made at this

time, it will be understood, because it is now no longer necessary to operate through the intermediate distributing frame IDF because all of the code digits have been transmitted, and the remaining digits to be transmitted 50 are subscriber digits and they are sent out untranslated and may therefore be transmitted independent of the common impulsing machine and one right after the other with only the usual trunk hunting time between 55 digits and without waiting for a fixed pick-up position to be reached before the next digit is transmitted, as is the case with the code digits.

To continue with the operation, it will 80 now be seen that wiper 115 is connected to ground through conductor 120 and through armature 223 and its working contact and that it is standing upon the bank contacts with which the first subscriber digit stop 85 conductor 141 is connected through the working contact and armature 225. Accordingly, in case the subscriber is slow about operating his calling device and has not yet transmitted the first subscriber digit 90 in the desired number, the ground potential applied to the conductor 141 is extended through the wiper of the digit register DR-1 and its normal bank contact to stop relay 95 206 by way of conductor 256, and the stop relay is held energized to prevent the transmission of the first subscriber digit from beginning, and, being slow acting, it does not fall back to permit such transmission to start until a slight interval of time has 100 elapsed after the wiper of the digit register DR-1 has been moved off normal in response to the dialling of the first subscriber digit. This insures that the sending apparatus can not function ahead of the registering apparatus and insures also that the digit register will get a sufficient start over the sending apparatus to insure that the sending apparatus will not overtake the digit register in case the calling device is somewhat 105 slower in its operation than the sending apparatus.

In the present case we may assume that the first subscriber digit is registered before the transmission of the office code is completed and that the calling subscriber continues to manipulate his calling device right along and that the sending apparatus does not catch up until the complete number is dialled. That being the case, the falling back of stop relay 206 is not retarded by the ground potential applied to the first subscriber digit stop conductor 141 by wiper 115 of the sequence switch S' and stop relay 206 falls back in the usual manner responsive to the opening of its circuit by pick-up relay 205, whereupon ground is applied to the upper terminal of the impulse relay 204 at armature 237 through armature 221 and its working contact. Accordingly, impulse 125 130

relay 204 starts to energize and deenergize under the control of the interrupter 305, Fig. 4, in the usual manner, and, upon the first energization of relay 204, a circuit is closed at armature 257 for the first counting-relay-control relay 208 as follows: From ground by way of the working contact of armature 224 of change-over relay 201, armature 257 and its working contact, relay 208, conductor 252, resting contact and upper armature of pick-up relay 403, resting contacts and upper armatures of counting relays 411-420, inclusive, and resistance 401 to battery. Upon energizing over this circuit, relay 208, Fig. 3, closes at armature 240 a locking circuit for itself over conductor 255 which includes the normally closed contacts controlled by the inner lower armature of pick-up relay 403, pick-up relay 403, locking conductor 242, resting contact and armature 238, and armature 228 and its working contact. This locking circuit does not become effective at this time, however, owing to the fact that the initial circuit of relay 208 is still established.

Upon the following deenergization of impulse relay 204, the initial circuit of relay 208 is opened at armature 257, whereupon pick-up relay 403, Fig. 5, energizes in series with the first counting-relay-control relay 208 over the previously traced locking circuit for relay 208; closes a locking circuit for itself and opens its initial circuit at its inner lower armature, whereupon relay 208 deenergizes; prepares a circuit for the first counting relay 411 at its lower armature; disconnects battery from conductor 252 associated with relay 208 and connects it instead to conductor 253 associated with the second counting-relay-control relay 209; and at its upper armature places ground upon conductor 251, thereby closing a circuit for pick-up relay 205. Pick-up relay 205 thereupon energizes and removes at armature 232 the shunt from around the armature 230 and its resting contact in addition to applying ground to conductor 116 to energize stepping magnet 113 of the sequence switch S' preparatory to advancing the wipers 114 and 115.

The pick-up step of the counting relay apparatus has now been taken to insure against a short first interruption in the outgoing control circuit, and, upon the next energization of impulse relay 204, a circuit is closed for the second counting-relay-control relay 209 which includes conductor 253, working contact and inner upper armature of pick-up relay 403, and thence to battery by way of the resting contacts and armatures of relays 411-420, inclusive, and the resistance 401. Relay 209 accordingly energizes and closes at armature 241 a locking circuit for itself which includes conductor 254, lower armature and working contact of pick-up relay

403, normally closed contacts controlled by the inner lower armatures of the relay 411, and the grounded conductor 242. This locking circuit is not effective at this time, however, owing to the fact that the initial circuit is still established, but, upon the deenergization of relay 204, the initial circuit of relay 209 is opened, whereupon the locking circuit becomes effective and the number 1 counting relay 411 energizes in series with relay 209; closes a locking circuit for itself and opens its initial circuit at its inner lower armature, whereupon relay 209 deenergizes; prepares a circuit for subsequently operating relay 412 over conductor 255 at the next lower armature; shifts battery at its upper armature from conductor 253 of relay 209 back to conductor 252 of relay 208; and at its lower armature connects up stop conductor 256. It is now seen that the first interruption in the series of interruptions comprising the first subscriber digit has been produced by relay 204 and that stop conductor 256 is connected to the first impulse stop conductor 431. Accordingly, if the first subscriber digit registered on the digit register DR-1 is the digit 1, stop relay 206 now energizes and terminates such digit. However, for the purpose of illustrating better the operation of the counting relays, it will be assumed that the first subscriber digit is the digit 0. Accordingly, the wiper of the digit register DR-1 is in engagement with its last bank contact, which is the bank contact in which the tenth impulse stop conductor 440 terminates, and stop relay 206 is, accordingly, not operated at this time.

Since the first subscriber digit is 0, according to the above assumption, the control relay 208 to which battery is now connected through conductor 252 operates upon the next energization of impulse relay 204 and locks itself through the second counting relay 412 which accordingly energizes upon the opening of the initial circuit of relay 208 and connects conductor 256 to the second impulse stop conductor 432, at the same time preparing the circuit for the operation of relay 209 and the third counting relay 413 upon the next operation of the impulse relay 204.

In this manner, the operation of the counting relays continues under the alternate control of the counting-relay-controlling relays 208 and 209 until the number 0 counting relay 420 energizes, at which time ten interruptions have been produced in the outgoing control circuit at armature 230 of relay 204, whereupon conductor 256 is connected with the tenth impulse stop conductor 440 and stop relay 206 energizes over the following circuit: from ground by way of the working contact and armature 223 of change-over relay 201, conductor 120, wiper 115 of the sequence switch S' , working contact and armature 225 of relay 201, the first sub-

scriber digit stop conductor 141, wiper of the digit register DR-1, the last associated bank contact, the tenth impulse stop conductor 440, lower armature and working contact of the tenth counting relay 420, stop conductor 256, and stop relay 206, Fig. 3, to battery. Upon energizing, stop relay 206 disconnects impulse relay 204 at armature 237; opens the circuit of stepping magnet 113 of the sequence switch S' at armature 236, whereupon the wipers 114 and 115 are advanced another step; also closes a locking circuit for itself at armature 236; and at armature 238 removes ground from conductor 242, thereby 15 opening the locking circuit of pick-up 205 and the locking circuits of relays 403 and 411-420, inclusive. Relays 403 and 411-420, inclusive, deenergize immediately but pick-up relay 205, as pointed out hereinbefore, 20 being slow acting, maintains its armature attracted for an interval, after which it deenergizes and opens the locking circuit of stop relay 206 at armature 238 responsive to which stop relay 206 deenergizes after a 25 short interval and again applies ground to conductor 242 at armature 238, and connects up the impulse relay 204 again at armature 237.

The grounded stop conductor wiper 415 of the sequence switch S' is now standing upon the bank contact in which the second subscriber digit stop conductor 142 terminates, and the wiper of the digit register DR-2 is accordingly grounded and, as 30 a result, stop relay 206 is energized as soon as the counting relay corresponding to the conductor upon which the wiper of the digit register DR-2 is standing is operated, terminating the second subscriber digit in the 35 usual manner, whereupon the wipers of the sequence switch S' are again advanced and the wiper of the third digit register DR-3 is grounded over conductor 143 to terminate the third subscriber digit upon the 40 completion of its transmission, whereupon the wipers of the sequence switch S' are still again advanced and the wiper of the fourth digit register DR-4 is grounded over the fourth subscriber digit stop conductor 144.

Upon the termination of the fourth subscriber digit, the wipers 114 and 115 are again advanced upon the opening of the circuit of stepping magnet 113 at armature 237 of stop relay 206, and wiper 115 applies ground to switching conductor 116, thereby closing a circuit over conductor 65, wiper 61 of the director selector DS, working contact and armature 57, and armature 45 and 55 its working contact, for switching relay 43 of the trunk circuit TC. Switching relay 43 now energizes and locks itself to conductor 40 at armature 50, and at armatures 49 and 51 disconnects conductors 36 and 38 from the 60 windings of line relay 41 and connects them 65

instead to the line conductors of the selector S, at the same time disconnecting the said line conductors from the closed bridge extending through the upper wipers of the director selector DS to the director, thereby 70 leaving the established connection under the direct control of the calling subscriber.

It may be pointed out now that the desired connection has been established and that the calling subscriber's bell is being 75 rung in the usual manner.

In the trunk circuit TC, line relay 41 de-energizes responsive to being disconnected by relay 43 and opens the circuit of release relay 42 at armature 44. Accordingly, release relay 42 deenergizes after a slight interval; removes ground from conductor 40 at armature 47, leaving the established connection held up over test wiper 97 of the selector S; opens a further point in the test 80 circuit of the director selector DS at armature 48; and at armature 46 opens the circuit of switching relay 52 of the director selector DS, whereupon relay 52 deenergizes, 85 freeing the director. 90

In the director, ground is removed from release trunk conductor 64 when the director is freed, as above pointed out, thereby opening the circuit of the holding relay 203 and the locking circuit of the lower winding of 95 relay 201. Holding relay 203 now deenergizes; grounds at armatures 227 and 227' all the contacts in the bank of the restoring wiper 114 of the sequence switch S' with the exception of the normal contact, whereupon the upper winding of relay 201 is short circuited and the said relay 201 deenergizes. Also, a circuit is closed through the last 100 contact in the bank of wiper 114 and the said wiper for stepping magnet 113 which 105 operates to automatically advance the wipers 114 and 115 to their normal position. As a further result of the deenergization of the holding relay 203, it applies ground at armature 229 to the release conductor 117, thereby closing a circuit through off normal contacts 328 for release magnet 327 of the office register OR, whereupon release magnet 327 energizes and the wipers 110 of the office register are restored to normal 115 position in the usual manner and the circuit of release magnet 327 is opened upon the opening of off normal contacts 328 when the switch shaft reaches its normal position.

The sequence switch S and the digit registers DR-1-DR-4, inclusive, are restored to normal position in a similar manner. The director is now in a normal condition and may be used in handling another call. 120

When the called subscriber responds to the ringing of his bell by removing his receiver, the flow of current in the calling subscriber's loop is reversed in the usual manner responsive to the energization of the back bridge relay of the connector. When 125 130

this occurs, the current flow is, of course, reversed in the upper winding of the electro-polarized relay 71 and relay 71 energizes for the first time; short circuits the resistance 84 between conductor 40 and conductor 37 at armature 85; and, just before its armature proper (not shown) has reached the limit of its stroke, short circuits its upper winding and the resistance 83 at armature 86 so as to provide a better talking circuit. The construction and adjustment of this relay is such that although the lower winding alone is unable to operate the armature proper of the relay, it is able to maintain the armature proper of the relay attracted after it has once been pulled up. Responsive to the short circuiting of the resistance 84, the marginally adjusted meter M is operated due to the increased current flow through the winding of the magnet 17, and registers the completed connection.

The calling and called subscribers may now converse with each other in the usual manner and when the conversation is completed they both replace their receivers. When the receiver is replaced at the called substation, the current flow in the calling subscriber's loop is reversed back to normal but the electro-polarized relay 71 does not now deenergize because, owing to the fact that its upper winding is short circuited at armature 86, it is removed from the control of the current flow in the calling loop.

When the receiver is replaced at the substation A, the ground potential is shortly removed from release trunk conductor 99 of the trunk seized by the selector S in the usual manner, whereupon switching relay 76 of the selector S, electro-polarized relay 71, and switching relay 43 of the trunk circuit TC deenergize. Also, the circuit of the slow acting line relay 16 of the line switch LS is opened and it deenergizes shortly and opens the circuit of relay 15 which deenergizes. The deenergization of switching relay 76 of the selector S results in the usual release magnet circuit being closed at armature 94 which includes armatures 87 and 88 and off normal contacts 78, whereupon release magnet 77 energizes and the selector is restored to normal position in the usual manner.

Regarding the utility of the small condenser 39, which is connected between the line relay 37 and one limb of the outgoing control circuit, coming from the director through the upper wiper of the director selector DS, it may be pointed out that this condenser is of a very small capacity and is just high enough to enable the calling subscriber to hear the interruptions being produced by the director as it operates to complete the establishment of the connection after the calling subscriber has completed the dialling of the number and is

waiting for the ringing of the called subscriber to begin. This has the effect of making a prolonged wait, in case there is one, such, for example, as on calls to offices having long office codes, seem less tedious, 70 and has the further utility of informing the calling subscriber that the exchange equipment is operating.

Referring now particularly to Fig. 1, it may be readily seen that when the line of substation A is called, switching relay 15 is pulled up upon the application of the ground potential to private normal conductor 13 and disconnects the line conductors 11 and 12 from line relay 16 and 80 ground, respectively, at armatures 18 and 22, but these conductors are not extended through to the line wipers 28 and 31 because line relay 16 is not at this time energized, as is the case when a call is originated on 85 the line of substation A.

As hereinbefore pointed out, the line switch LS is provided with two test wipers 29 and 30. The reason for this will now be fully explained. Wiper 29, in addition to 90 being used as a test wiper, is used also as a holding wiper and current is supplied to this wiper from conductor 37 for holding up line relay 16 on an outgoing call, as hereinbefore pointed out. Now, if test wiper 95 29 alone was provided for the line switch LS, i. e., if test wiper 30 and the associated connections were omitted, the line switch LS would still operate and would be largely 100 successful. However, one or two undesirable operating features would be present. In the first place, it is always desirable to make a seized trunk busy immediately upon seizure. This would not be done if test wiper 30 were omitted because ground is not supplied to release trunk conductor 37 from 105 conductor 40 until the line and release relays 41 and 42 of the trunk circuit TC have pulled up one after the other in response to the seizure of the associated trunk. Furthermore, the release trunk conductor 37 110 could not then be used as a meter operating conductor in the manner shown in the drawings, because it is impractical to depend upon ground supplied through the resistance 84 115 to operate the stepping magnet 14 of the line switch LS and the conductors 37 and 40 would have to be joined directly together.

The second undesirable operating feature 120 present in case only the test wiper 29 is provided, is that the trunk last seized by the line switch LS would be rendered idle to the other line switches immediately upon the removal of the ground potential from conductor 37 upon the release of the connection 125 and the same trunk might be immediately seized by another searching line switch before the slow acting line relay 16 could deenergize and disconnect itself from test wiper 29.

Considering now on the other hand the operation of the line switch LS, in case the test wiper 30 is provided with wiper 29 acting only in its capacity as a holding and meter operating wiper, i. e., with the back contact of armature 20 and the associated conductor removed, the operation of the line switch is obviously perfect as regards seizing a trunk because the seized trunk is made busy immediately upon the operation of armature 21 of relay 15, and the seized trunk is not rendered idle upon the release of the connection until line relay 16 deenergizes and opens the circuit of switching relay 15 at armature 25, whereupon the ground potential is removed from conductor 34 at armature 21. However, under the conditions above set forth, it is not possible to render the trunk extending to the selector S from the line switch bank through the trunk circuit TC busy from the selector S, and the jack J has no utility under this condition, but, with test wiper 29 wired up as shown, release trunk conductor 37 may be grounded at will at the selector S by an attendant, who, for this purpose, may insert any piece of conducting material of the proper size and shape between the springs of the jack J.

A careful study of the drawings will reveal that, with the line switch LS operated on an outgoing call, and with the electro-polarized relay 71 not yet operated, the full ground potential is supplied to the marginal meter M whenever another searching line switch passes over the multiple terminals of the trunk extending to the trunk circuit TC, because of the fact that the test wipers corresponding to the test wipers 29 and 30 of the line switch LS are connected together and the ground potential, therefore, which is on conductor 34 is extended through the two test wipers in series of the searching switch to conductor 33, and thence to the magnet 17 of the meter M through test wiper 29 and armatures 14 and 19. The meter M is not operated under such a condition, however, owing to the fact that the time during which the above described circuit is established is very short owing to the high speed at which the line switches travel. Furthermore, due to the mechanical construction of a meter such as M, a meter does not operate nearly so quickly as a stepping magnet and the searching line switch has passed beyond before the meter can get started to pull up.

What is claimed is:

1. In a two-motion automatic switch, a primary operating magnet, a slow acting change-over relay, means for sending impulses to said operating magnet and said change-over relay simultaneously, and contacts on said operating magnet for disconnecting said change-over relay from the impulse circuit.

2. In a call director, an office register, mul-

iple connections between the bank contacts of said office register and the bank contacts of office registers in other directors, a counting switch, multiple connections between the banks of said counting switch and the banks of said office registers, an impulse conductor leading to each of said directors, and means for sending impulses over said impulse conductors and for advancing said counting switch in synchronism with said impulses. 70 75

3. In a relay counting device, a series of counting relays and two priming relays, a circuit for transmitting impulses to said priming relays, circuit connections for energizing the first priming relay upon the receipt of the first impulse, contacts on said first priming relay for closing a locking circuit for itself including the first of said counting relays whereby the first counting relay is energized in series with the first priming relay when the initial circuit of the first priming relay is opened when the first impulse subsides, contacts on the first counting relay for disconnecting the first priming relay and for connecting up the second priming relay, contacts on the second priming relay corresponding to the said contacts on the first priming relay but connected to the second counting relay, contacts on the second counting relay for disconnecting the second priming relay and for connecting up the first priming relay, contacts on the remaining odd numbered relays corresponding to said contacts on said first counting relay, and contacts on the remaining even numbered counting relays corresponding to the said contacts on said second counting relay. 80 85 90 95 100

4. In a telephone system, a plurality of directors, a common distributing frame, an office register in each director having its bank connected to one side of said frame in multiple with the banks of the office registers in the other directors, and a counting switch having its bank connected to the other side of said frame. 105 110

5. In a telephone system, a plurality of directors, a common distributing frame, an office register in each director having its bank connected to one side of said frame in multiple with the banks of the office registers in the other directors, a counting device having a plurality of digit contacts, and connections from said contacts to the other side of said frame. 115

6. In a telephone system, a plurality of directors, each including a register and a sender, and a common counting device for controlling the sender in each director by means of the associated register. 120

7. In a telephone system, a plurality of directors, each including a register and a sender, and a step by step counting switch common to said directors for controlling said senders by means of the associated registers. 125

8. In a telephone system, a plurality of di-

rectors, each including a register and a sender, a step by step counting switch common to said directors for controlling said senders by means of the associated registers, 5 and means for operating the said senders in synchronism with said counting switch.

9. In a telephone system, a plurality of directors, each including a register and a sender, a common counting device for controlling the sender in each director by means of the associated register, and a common distributing frame intervening between said counting device and the banks of said registers.

10. In a telephone system, a plurality of directors, each including a register and a sender, a step by step counting switch common to said directors for controlling said senders by means of the associated registers, 20 and means for preventing the starting of any sender except when said counting switch is in a particular position.

11. In a telephone system, a plurality of directors, each including a register and a sender, a common counting device for controlling the sender in each director by means of the associated register, and means for starting each sender at a particular point in the operation of said counting device.

30 12. In a telephone system, a plurality of directors, each including a register and a sender, a common counting device for controlling the sender in each director by means of the associated register, and means for starting a sender co-ordinated as to time with the operation of the counting device so that the sender starts transmitting impulses when the counting device starts counting.

40 13. In a telephone system, a plurality of directors, an impulse transmitting relay in each director for producing series of impulses, a stop relay in each director for terminating the impulse series, and a common counting device for controlling all said stop relays.

45 14. In a telephone system, a plurality of directors, an impulse transmitting relay in each director for producing series of impulses, a stop relay in each director for terminating the impulse series, an individual interrupter for operating each transmitting relay, and a common counting device for controlling all said stop relays.

55 15. In a telephone system, a plurality of directors, an impulse transmitting relay in each director for producing series of impulses, a stop relay in each director for terminating the impulse series, a common device including a plurality of synchronous 60 interrupter circuits over which a plurality of said interrupters control said plurality of transmitting relays, a common counting switch for controlling said stop relays, and a circuit over which another of said interrupters controls said counting switch.

16. In a telephone system, a plurality of directors, an impulse transmitting relay in each director for producing series of impulses, a stop relay in each director for terminating the impulse series, a common 70 counting device, and means including a register in each director for placing the associated stop relay under the control of said counting device.

17. In a telephone system, a plurality of directors, an impulse transmitting relay in each director for producing series of impulses, a stop relay in each director for terminating the impulse series, a common 75 counting device, a register in each director having a plurality of wipers, each wiper for preparing a circuit between the associated stop relay and said counting device, and a sequence switch in each director for connecting the associated stop relay in circuit with the several wipers of the associated register successively.

18. In a telephone system, a plurality of directors, each including a sender, an office register, and digit registers, a counting device common to said directors for controlling said sender by means of said office register, and a counting device individual to each director for controlling the sender in the associated director by means of the associated digit registers.

90 19. In a telephone system, a plurality of directors, each including a sender, an office register, and digit registers, a counting device common to said directors for controlling said sender by means of said office register, a counting device individual to each director for controlling the sender in the associated director by means of the associated digit registers, and means automatically effective upon the transmission of the last office digit by said sender for shifting the control of the same from the common counting device to the said individual counting device.

100 20. In a director, a register for selecting an office code, a sender, means including a sequence switch having a plurality of positions for causing said sender to transmit the digits of a selected code, means including a stop conductor and a stop relay for terminating each digit of a code being transmitted, and a marginal relay included in said stop conductor for automatically advancing said sequence switch through the surplus positions whenever a code is transmitted having less than the maximum number of digits.

115 21. In a telephone system, a director, an office register having a plurality of wipers, a distributing frame having terminals on one side connected in multiple with the bank of said register, digit bus bars on the other side of said frame and a battery bus bar, jumpers connecting certain of said termi- 120 125 130

nals to digit bus bars and certain other terminals to said battery bus bar, a sender in said director, means including a sequence switch effective after the said register has been set to place the said sender under the control of said wipers successively, and means for automatically advancing the sequence switch to skip wipers whenever the sender is associated with a wiper resting on 10 a bank contact associated with a terminal which is connected to said battery bus bar.

22. In combination, an impulse responding device including an operating magnet arranged to operate said device, a slow acting 15 change-over relay, means for sending impulses to said magnet and to said relay, and contacts on said magnet for terminating each impulse to said relay.

23. In a step-by-step automatic switch, a 20 driving magnet for operating said switch, a slow acting change-over relay, means for transmitting impulses of variable length to said relay and to said magnet, and means controlled by said magnet for altering the 25 impulses delivered to said relay so that they are all of substantially the same length.

24. In a director, a register for selecting an office code, a sender, means including a sequence switch having a plurality of positions 30 for causing said sender to transmit the digits of a selected code, means including a stop conductor and a stop relay for terminating each digit of the code being transmitted, a relay included in said stop conductor un- 35 responsive to the control exercised over said stop conductor to operate said stop relay, and means for operating the second named relay over said stop conductor to automatically advance said sequence switch through the 40 surplus position whenever a code is transmitted having less than the maximum number of digits.

25. In a telephone system employing serially related switches for setting up connections, a plurality of register controllers for controlling said switches, an impulse sending machine common to said register controllers and having a plurality of control leads corresponding, respectively, to the 50 different impulse series that may be transmitted by said register senders, means for operating the registering portion of any one of said register senders to select any one of said leads, and means including said sending 55 machine and said controller for transmitting a series of impulses corresponding to the lead selected.

26. In a telephone system, automatic switches, register controllers, a sending device having associated therewith primary control conductors corresponding, respectively, to impulse series of different lengths, a plurality of secondary control conductors multiplied throughout all said register controllers, a distributing frame at which any

secondary conductor can be connected with any primary conductor, and means for operating a train of said switches under the joint control of any one of said register controllers and said sending device, the said control being exercised through one of said secondary conductors through the connection made at said distributing frame with one of the primary conductors. 70

27. In an automatic telephone system employing a plurality of register controllers for controlling the automatic switches, an impulse sending device common to all said register controllers and having associated therewith ten primary digit conductors for 80 determining the length of impulse series, a greater plurality of secondary digit conductors multiplied to all of said register controllers, and a distributing frame at which any primary digit conductor can be connected to any conductor in said multiple. 85

28. In a director system in which impulse series are transmitted under the joint control of any one of a plurality of registers and a single sender, a distributing frame 90 whereat the value of the digit transmitted in accordance with a given set position of any register may be assigned at will.

29. In a telephone system, automatic switches, register controllers, a sending device common to said register controllers, and means for operating a train of said switches under the joint control of said sending device and any one of said register controllers, the extent of the directed movement of each 100 switch being governed by the common device. 95

30. In a telephone system, automatic switches, register controllers, a sending device common to said register controllers, and means for operating a plurality of trains of said switches contemporaneously, each train of switches being operated under the joint directive control of said sending device cooperating in each case with a different one 110 of said controllers. 105

31. In a telephone system, a plurality of directors, each including a register and a sender, and a progressively movable device common to all said directors, and means whereby said device cooperates with any operated register to cause the associated sender to transmit a series of impulses whose value is determined jointly by the register in question and the said device. 115 120

32. In a telephone system, a plurality of directors, a register in each director, an impulse circuit outgoing from each director, a progressively movable device common to all said directors, and means including a common distributing frame for causing said device to cooperate with any operated register to transmit a predetermined series of impulses over said circuit. 125

33. In a telephone system, a plurality of 130

directors, a progressively movable impulsive device common to said directors, said device including means for controlling the production of variable series of impulses, 5 means in each director for predetermining the value of a series of impulses to be produced by said device, and means in each director for directing such a predetermined series of impulses to an automatic switch.

10 34. In a telephone system, a plurality of directors, each including a register and a sender, a common impulsive device for operating said senders, means for placing any sender under control of said device, and 15 means common to all the senders and adapted to cooperate with the register associated with any operating sender to stop such sender.

20 35. In a telephone system, a plurality of controllers, each including a register and a sender, and a common counting device for controlling the sender in each controller by means of the associated register while such 25 register remains stationary in a set position.

30 36. In a telephone system, a plurality of controllers, each including a register and a sender, means for setting a register in any one of said controllers, and a counting device 35 common to all said controllers for controlling any sender by means of the associated register and in accordance with the position in which it has been set.

40 37. In a register sender system, a plurality of register senders, a plurality of digit conductors multiplied into a register in each of said register senders each conductor corresponding to a different digit, means for setting any register onto any conductor to predetermine a digit, and means for operating the sending portion of said 45 register senders simultaneously each in accordance with the setting of the associated register and without interference between the different senders.

50 38. In a register sender system wherein a sender is arranged to transmit a series of impulses of a value directly controlled through the associated register, a plurality of digit conductors each corresponding to a different digit and multiplied into a plurality of registers, each of said registers being in a different register sender, means for operating a plurality of senders simultaneously so that each sender is controlled over said multiple connections in accordance with the set position of its associated register to transmit a series of impulses of a value determined by the setting of the associated register and without interference from any other register sender.

55 39. In a register sender for use in a multi-office telephone system, an office register having a plurality of wipers, a stop relay for stopping successive sending op-

erations in accordance with the setting of said office register, and a sequence switch for connecting said stop relay to the wipers of said office register successively.

40. In a register sender a plurality of 70 registering devices, a stop relay for terminating the successive sending operations, said stop relay being connected at one terminal to a source of current, and means for connecting the other terminal of the stop 75 relay to said registering devices successively so that the several operations are terminated under the control of the several registering devices respectively.

41. In a register sender for use in a telephone system to send a plurality of digits, a plurality of digit conductors, a counting device arranged to apply potentials to said digit conductors successively, means for bringing said registering devices into engagement with certain ones of said digit conductors to predetermine the combination of digits to be transmitted, means for starting the sending operation to transmit the digits, a stop relay for terminating each of 90 the digits arranged to respond to the application of potential by said counting device, and means for connecting said stop relay to the first of said registering devices and for shifting it into connection with the 95 remaining registering devices successively as the respective digits are transmitted.

42. In a register sender for use in a telephone system and arranged to transmit a plurality of digits, a plurality of registering 100 devices, means for transmitting one of said digits and for controlling the value thereof in accordance with the setting of one of said registering devices responsive to potential applied to such device through the stop relay, 105 and means for controlling the value of the remaining digits by applying potential successively to the remaining ones of said registering devices over a circuit path independent of said stop relay.

43. In a register sender for retransmitting a plurality of digits in accordance with the setting of registering apparatus, two stop relays, means for terminating one of the transmitted digits by operating one stop relay and means for terminating a plurality of other digits by operating the other stop relay while the first stop relay is maintained nonoperated.

44. In a register sender for use in a telephone system to transmit a plurality of digits in accordance with the setting of a plurality of registering devices, two stop relays, means for terminating one digit of the plurality by operating both of said stop relays, and 125 means for terminating another of said digits by operating only one of said stop relays.

45. In a sending device, a stop relay, an auxiliary relay, means for terminating a series of impulses being transmitted by 130

the sender by operating said auxiliary relay to in turn operate said stop relay, and means effective when a different digit is being transmitted to terminate the last-named digit by directly operating the said stop relay without first operating said auxiliary relay.

46. In a register sender system for use in a telephone system to transmit digits, a plurality of register senders, a sending device common to said plurality, a local sending device for each of said register senders, a stop relay in each register sender arranged to cooperate with the common sending device to retransmit a digit of a predetermined value, and means effective thereafter for cutting out said stop relay and for rendering the

local sending device active to continue the sending operation.

47. In a register sender for use in telephone systems to transmit a plurality of digits in accordance with the setting of registering devices, a sending device common to a plurality of register senders, a sending device local to each of said register senders, means for operating a register sender under the control of said common sending device, and means effective thereafter for continuing the operation of the register sender under the control of its local sending device. 20 25 30

In witness whereof, I hereunto subscribe my name this 28th day of October, A. D., 1924.

JOHN I. BELLAMY.
